UNITED STATES PATENT OFFICE.

EDWARD E. CLEMENT, OF WASHINGTON, DISTRICT OF COLUMBIA, ASSIGNOR, BY
MESNE ASSIGNMENTS, TO THE NORTH ELECTRIC MFG. CO.

TELEPHONE-EXCHANGE SYSTEM.

Application filed April 20, 1907. Serial No. 369,201.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

My invention relates to telephone exchange systems, and particularly to semi-automatic systems in which automatic switches or their equivalent are employed to effect interconnection of lines as determined by manual apparatus controlled through the agency of operators. My invention has for its object the provision of a number of sets of switching apparatus sufficient for the probable needs of the service, but not necessarily equal to the number of lines, and most desirable less than the number of lines; the provision of operator's controlling sets less in number than the number of lines; and the distribution of the load, that is to say, the incoming calls, among sets of switching apparatus and among the operators, whereby uniform efficiency in service may be attained.

For the sake of simplicity in description I shall specify herein automatic switches of the type known as "Strowger" selectors and connectors, the construction of such switches being well shown in Letters Patent No. 815,176 and No. 815,321, granted to Keith and Erickson, March 13, 1906. The circuits commonly employed with these switches are well known to those skilled in the art. I shall also specify a type of common battery line circuits and central office talking circuits which are considered standard, and generally known as two-wire bridged battery circuits. It is to be understood however, that in specifying the apparatus and circuits mentioned they are used as types for purposes of description, and not as limiting the invention.

Stated in terms of the embodiment thus presented, the present invention comprises a number of groups of selector and connector switches less than the number of lines to be served; a number of primary selector switches normally set back to a fixed or zero position, and adapted to connect the calling

lines with said groups of selector and connector switches; a number of operators' 55 selective keys and impulse transmitting means controlled thereby, with automatic secondary selector switches normally set back at a zero or idle position, and acting to connect the trunks from the primary 60 selector switches to the operator's apparatus when the calls are received, whereby the operators may talk with the calling subscribers, and may actuate the appropriate selector and connector switches to connect 65 the calling and the wanted lines.

By having all the primary and secondary selector switches normally set back to zero, I effect a uniform distribution commencing 70 always with the first trunk or the first position. When a subscriber calls in, current in his line energizes a relay which starts up a primary selector switch, said switch continuing to progress step by step until its wipers connect the terminals of an idle 75 trunk, at which time the cut off relay of the line receives current from the switch circuit, the switch stops, and the secondary selector switch is started to connect the trunk to an idle operator's circuit. An appropriate signaling means such as a lamp, is provided for each operator's circuit, and the operator being thus apprised of a call is able to connect her telephone through her circuit to the trunk and thence to the calling 80 line, and afterward to transmit impulses to the trunk and forward to its automatic first selector switch to secure connection with the line wanted. Testing and ringing of the wanted line are automatic. 85

The specific distinguishing feature of the apparatus hereinafter set forth, is that each trunk has a terminal selector switch by which a subscriber's line may be connected in calling to an idle trunk line leading to a 90 first selector switch; and each operator's set is provided with a switch starting up from zero or normally in operative position to select and connect a trunk line with the controlling and talking circuit of an idle operator. The operator's circuit remains connected to the trunk as long as may be necessary to send the proper impulse for setting the switches, which complete the connection after which the selector switch governing 95 the operator's circuits is returned to zero. 100

My invention is illustrated in the accompanying drawings in which—

Figure 1 is a diagram showing a calling subscriber's line and a portion of the central office equipment,

Figure 2 is a similar diagram complementary to Figure 1, and intended to be placed below the latter, showing another portion of the central office circuits.

Figure 3 is a similar diagram also complementary to Figure 1, intended to be placed at the right of the latter, and showing a selector and connector switch with their circuits, through which the calling line may be connected with anyone of a considerable number of other lines,

Figure 4, is a diagram of circuits complementary to Figure 2, intended to be placed at the right of the latter,

Figure 5, is an end view of an improved rotary selector switch,

Figure 6 is a section on the line X—X of Figure 5,

Figure 7 is a similar view with the bank contacts removed, of a modification of the switch shown in Figure 5,

Figure 8 is a diagram showing connections whereby calls are distributed between the trunks so that one call may not operate several trunk connecting switches,

Figure 9 is a diagram showing connections between different operators' equipments and the trunks whereby calls are distributed between the said equipments so that one call may not operate several switches for connecting operator's equipments.

Referring to Figure 1, A is a subscriber's station connected to the central office by line wires 1 and 2 which are normally connected through the contacts of a cut-off relay N to the line relay M and the ground, respectively, the line relay being connected to the main battery B through the wire 3. Line extensions 4 and 5 extend from the cut-off relay to multiple bank contacts of switches S. Each switch S is a step by step selector and is what is called a "single motion" or rotary switch, having a spindle s journaled so that it can turn upon the axis and provided with a ratchet wheel by which it may be turned. This ratchet wheel is engaged by a stop or detent pawl controlled by the electromagnet s². The mechanical construction of this switch is shown in Figures 5, 6 and 7, which will be hereinafter particularly referred to. The circuit of the electromagnet s² is controlled by the line relay M through its armature m for which purpose the front contact 7 of the relay is connected by a wire 8 with the magnet s², while the armature m is connected through an interrupter I with a battery wire 3. This interrupter is continuously operating and may consist, as shown, of a rotative cylinder having alternating insulating and conducting

portions, one conductor being connected with the conducting portion and another with a pen bearing upon the cylinder, so that as the cylinder rotates the conductors will be alternately connected together and disconnected as the pen successively bears upon the conducting and insulating portions. The cylinder is continuously driven by any suitable means. With such an arrangement it is only necessary to maintain the circuit closed, when the successive energizations and deenergizations of the magnet and vibrations of its armature will continue indefinitely. In the present case as the magnet s² vibrates its armature, it also turns the spindle s by means of its pawl and a ratchet on the spindle, any retrograde motion of the spindle being prevented by the stop pawl controlled by the magnet s'. The spindle is provided with a return spring, preferably a coiled spring, which has a constant tendency to turn the spindle back against the pawl of the magnet s', and when this pawl is released by the energization of this magnet, will actually turn back the spindle to its normal, zero, or inoperative position. The circuit of the magnet s² in addition to being controlled by the line relay M, is also controlled by the relay R', of the trunk while the release magnet s' is controlled partially by the relay R.

In addition to the bank contacts 9 and 10 to which extensions 4 and 5 of the subscriber's line are connected, each switch S is provided with multiple test contacts 11. The wipers 12 and 13 of the switch are adapted to engage, respectively with the bank contacts 9 and 10, while a test wiper 14 is adapted to engage with the bank contacts 11. From the wipers 12 and 13 are trunk extensions 15 and 16, the connection of which with the trunk lines 17 and 18 is controlled by a trunk cut-off relay N', which is controlled by the relay R.

The relays R and R' are bridged between the two trunk conductors with the main battery between them. The tip relay R is connected at one side with the conductor 17, the other side being grounded, while the sleeve relay R' is at one side connected to the free side of the battery B and at the other side to the trunk conductor 18. The tip relay R responds to the act of the calling subscriber and controls the clearing out of the automatic apparatus; the sleeve relay becomes energized when the switch S picks out an idle trunk and then closes the circuits of the magnets R² and R⁴ which are respectively the stepping magnet of the secondary or operator selector switch S' and a locking relay serving also as a cut-off relay for shifting the control as the operator's circuit is connected. The functions of these several relays will best appear from the statement of their operation hereafter.

The relays R^5 and R^6 are combined cut-off and repeating relays. The relay R^5 when energized over the operator's wire 19 pulls up its armature, breaks apart the trunk wires 21 and 23 and connects the latter to the wire 25 leading to the free terminal of the battery B, so as to send an impulse of current through the trunk wire 23. When the relay R^6 is energized over the operator's wire 20 it pulls up its armature to break apart the trunk wires 22 and 24 and connects the latter to the wire 26 which is connected to the free terminal of the battery B, thus sending an impulse of current forward over the trunk wire 24. When both of the relays R^5 and R^6 are simultaneously energized, they connect the operator's wires 20 and 19 to the trunk wires 21 and 22, respectively, so that the operator may connect her telephone to the wires 21 and 22 and communicate with the calling subscriber. It will be observed that the wires 21 and 22 are extensions of the trunk conductors 17 and 18, respectively, to which they are connected by means of condensers C, the condensers being provided to prevent confusion of battery current between the answering and calling ends of the trunk section. It will also be seen that the conductors 23 and 24 are respectively extensions of the trunk conductors 21 and 22.

The test contact 14 is connected by a wire 27 with a contact 28 through which circuit is broken when the relay R is energized and, therefore, when the trunk is in use. When the trunk is not in use, and its switch S has been stepped into position to connect it with a calling line connection may be traced from the wiper through conductor 27, contacts 28 and 29, conductor 30 and cut-off relay N' to ground.

It will have been observed that there is one switch S for each trunk, and in order that the switch of an idle trunk may be set in operation to connect a calling subscriber with that trunk, suitable apparatus is provided and further the apparatus is so constructed and arranged that it is impossible for a single call to set in operation more than one trunk switch at a time. The arrangement of the apparatus by which these results are accomplished, is shown in Figure 8 from which figure portions of the apparatus which are not necessary to an explanation of the features under consideration, have been omitted. Referring particularly to Figure 8, it will be seen that the conductors 8, 8' and 8² which lead respectively to the stepping magnets s^2 , 1^{s2}, 2^{s2} and etc. of the respective selector switches S, 1^s, 2^s and etc., are connected together by a conductor 31 so that the energization of any line relay M, 1^M or 2^M at any subscriber's station will operate to connect one side of the battery B through the interrupter I with all

of the stepping magnet s^2 , 1^{s2} and etc. It will be noted however, that the ground connections of these stepping magnets are made through the back contacts of the armatures r' , 1^{r'}, 2^{r'} and etc. of the sleeve relays R', 1^{R'}, 2^{R'} and etc. It will be observed, however, that although the ground connection of each of these stepping magnets is made through the back contact of its particularly armature r' , 1^{r'} or 2^{r'}, the circuit thus partially made must be completed through the forward contacts of all of those armatures at one side of the armature in question. These forward contacts are only connected when their controlling relays are energized and therefore, only when the trunks to which they correspond are in use. It will now be apparent that it will be impossible for two trunk selector switches to be set in operation by the same call and also that the trunks will be progressively selected by succeeding calls. To illustrate, assuming that none of the trunks are in use, the armature r' is the only one connected with ground as shown in the figure. If now a call is initiated by a subscriber, intermittent battery connections will be made with all of the stepping magnet s^2 , 1^{s2} and etc. The magnet s^2 , however, being the only one having ground connection, this magnet will be the only one energized and will step its switch S into connection with the calling subscriber's line, the other switches 1^s, 2^s and etc. remaining unaffected. The trunk corresponding to the switch S having been thus placed in use, sleeve relay R' will be energized and the ground connection through the armature r' will be placed upon the forward contact so that armature is connected with the next armature 1^{r'} of a succeeding trunk. Ground is thus placed upon one side of the stepping magnet 1^{s2} so that upon a succeeding call from a subscriber the stepping magnet 1^{s2} will be energized, as was the magnet s^2 and the switch 1^s will be stepped into position to connect the second calling subscriber with the trunk corresponding to the switch 1^s. This second trunk having been placed in use, the armature 1^{r'} of this trunk will make a ground connection through its forward contact for the armature 2^{r'} and stepping magnet 2^{s2} of the succeeding trunk and this operation of causing each trunk as it is brought into use to establish connections for the bringing of a succeeding trunk into operation upon the initiation of another call, is carried out to the limit of the apparatus.

With the apparatus thus described it will be seen that if a stepping magnet as 2^{s2} is receiving impulses through armatures as r' and 1^{r'} of other trunks, and is stepping its switch 2^s to connect its trunk with the calling subscriber, and either or both of the trunks through which the circuit of the mag-

net 2^{s2} is made, is or are cleared out, one or both of the armatures r' and $1'$ will fall back and the circuit of the magnet 2^{s2} will be broken and the operation of the magnet 5 will cease, leaving the switch 2^s in whatever position it happened to be and confusion of the apparatus might result. To avoid this, contacts a' and b' are provided for each trunk selector switch except the one having 10 its stepping magnet connected with ground through an armature of its own trunk. The mechanical arrangement of these contacts is shown in Figure 7 which will be referred to hereafter; these contacts are normally closed 15 but are separated when the switch is in zero position. One of the contacts is connected with the stepping magnet of its switch while the other is connected to the ground. The ground connection of the stepping 20 magnet is broken at these contacts when the switch is in zero position but after the switch has once left that position, the ground connection of the stepping magnet is maintained through these contacts until 25 connection is established with the calling subscriber's line regardless of whether trunks, through which the initial connection for the stepping magnet was made, are cleared out or not.

30 The trunk wires 23 and 24 extend as shown in Figure 3 to the side-switch arms s^{10} and s^{12} of the selector switch S^2 . This switch is of the Strowger type referred to in the beginning of my specification, having 35 a main spindle arranged for both vertical and rotary movements, this spindle being placed at the axis of a set of contacts arranged in ten rows of ten each. Carried on the spindle are talking-circuit wipers s^{16} which co-operate with the bank contacts s^{18} and a test wiper s^{20} which cooperates with the multiple test contacts s^{22} . The switch spindle is stepped up to bring its wipers opposite the desired row of contacts by 40 means of the so-called vertical magnet v controlled through a relay V ; and the rotary movement of the switch is brought about by means of a vibrator magnet v' which makes and breaks its own circuit as it vibrates and 45 is controlled by the relay T when the side switch arm s^8 is in its second or intermediate position. It is unnecessary to give here any extended description of the circuits and apparatus of Figure 3, all of these being old and well known to those skilled in the art. Q is a release relay of the switch and q is the release magnet governed thereby. The other parts of the apparatus as well as the circuit connections will sufficiently appear 50 from the statement of operation hereinafter.

55 S^3 designates a connector switch which is designed to cooperate with a selector switch S^2 . It has a similar spindle carrying wipers s^{24} . The test is made on the tip or upper side of the line. The switch also contains

line contacts in its banks arranged in rows of ten each. The spindle is stepped up to bring the wipers s^{24} opposite the desired row by means of a so-called vertical magnet v' and is rotated step by step by means of a so-called rotary magnet v , which in this case is not a vibrator but responds to distinctive current impulses, since the desired line is identified with a single pair of contacts only, and therefore the row of contacts must be 70 selected and the pair of contacts in the row afterward picked out by the wipers, before testing. In this resides the principal difference between the connector and selector switch, the purpose of the selector switch 80 being to pick out and connect with an idle trunk line in any desired group. In the operation of the selector switch, therefore, the spindle is stepped up by means of definite and distinctive impulses to the row of contacts s^{18} and s^{22} representing the desired group (which may be either thousands or hundreds and in this case is hundreds), and after that, when the side switch has taken one step, the rotary magnet v' takes control 85 of the switch and steps the spindle around continuously as long as the wiper s^{20} finds ground on the contacts s^{22} . When this ground fails (the busy contacts being 90 grounded and the idle ones open) it means that an idle contact has been reached, and thereupon the side switch is moved a third step to cut off the rotary magnet and step the wipers upon this ungrounded or idle contact.

95 The connector circuit contains a pair of condensers C' for the reason that the forward impulses which work the switch must not be confused by the battery current supplied to the called subscriber. We may assume that the switches of Figure 3 are both in the same building with the apparatus of Figures 1 and 2 although this is not at all necessary, and in such case the battery B shown separate in the two figures is of course the same battery. For the purpose of supplying talking current to the called subscriber, I connect this battery to the sleeve conductor 44 of the connector switch through a relay R^s , and I ground the tip conductor 43 through the relay R^t which is the same as connecting it back to the battery. Thus, the main battery is also bridged across the conductors 43 and 44 through the relays R^t and R^s which as in the case of the relays R and R' in Figure 1 are wound to 105 approximately 100 ohms each, but present high impedance to voice currents. R^s is the ringing relay, which controls the application of the ringing generator G to the called line and is itself controlled on the one hand by the relay R^{10} and on the other by the commutator K , which may be common to all the ringing relays of the exchange. The circuit of the ringing relay is indicated at 110

115

120

125

130

45, 46, 47, 48, 49 and 50, being terminated at the ground through the commutator on one end and at the battery wire 3 on the other end. This circuit is controlled by the 5 relay R^s , and this relay does not become energized until the side-switch arms s^9 , s^{11} , s^{13} and s^{15} have made their last step so that the conductors 43 and 44 are completed from the condensers C' to the wipers s^{24} . Before 10 this last step of the side-switch is taken, the wipers s^{24} have been placed upon the terminals of the wanted line, and the release relay Q' has been applied to the tip side of the line for the purpose of testing. The 15 circuit of this relay is as follows: 51, 52, 53, 54, 55, s^{15} , 56 to the tip wiper s^{24} . If the line wanted is busy, there is a ground on the tip side, either by way of a relay R or by way of a relay R^7 , depending on whether 20 the line originated the call upon which it is engaged, or was called by some other party. In either case the test or release relay Q' will receive current; but if there is no ground because the line wanted is idle, 25 then the test relay remains unaffected, the talking circuit is completed, and the sleeve relay R^s becomes energized by current passing to the sleeve wiper s^{24} and thence through the multiple contact 10 (see Figure 1) and 30 the cut-off relay N to ground. The cut-off relay thereupon pulls up and the ringing relay circuit is at the same time completed so that the commutator K takes control thereof. It will be observed that this circuit 35 46-47, etc. passes through a back contact on the relay R^{10} , which is controlled on one side by a pair of contacts under the foot of the spindle of the switch s^9 , and on the other side by front contacts of the 40 tip relay R^7 which does not pull up until the called subscriber answers. When this occurs, the relay R^{10} becomes energized, locks itself by way of wires 50 and 57, and opens 45 the ringing relay circuit 46, 47, 48, etc. The relay R^s is controlled by the subscriber in the intervals of ringing, for it will be observed that the commutator K has segments whereby it closes the ringing circuit at intervals only. While this circuit is open, 50 therefore, and the relay R^s deenergized in consequence, the subscriber has control of the relay R^7 . In order that the relay N may remain energized through the ringing intervals, I provide a special battery connection, as shown.

The arrangement of switches shown in Figure 3 is sufficient for exchanges up to 1000 line capacity; but in order to provide for more than 1000 lines, another set of selector switches is required, interposed between the trunk ends of Figure 1 and the switch S^2 of Figure 3. The capacity of the exchange can be increased indefinitely without altering these circuits by adding these sets or groups of switches in the well

understood manner. The selector switches all have the same circuit as that shown at S^2 and therefore I have considered it unnecessary to multiply illustration by showing more than one. It is within the power 79 and skill of every person having a fair knowledge of the automatic art to add as many sets of selectors as may be desired. Regardless of the number of switches, the 75 method of operation, which has an important bearing upon the operator's equipment, is to send the selecting or working impulses over the trunk wire 21, which is commonly called the vertical wire, and to send the controlling impulses over the trunk wire 22 which is commonly called the rotary wire. These so-called rotary impulses serve to work the side-switch magnets T and T' , and thereby to shift the side switches so as to bring into play successively the vertical and rotary magnets, the test relay, etc.

Referring now to the lower part of Figure 1 and to Figure 2, there is therein shown, 80 an operator's equipment and its selector switch for connecting a called trunk therewith. The selector switch is marked S , and is similar in its construction to the primary selector switch S . It has a spindle s^{28} and wipers s^{29} , s^{30} and s^{31} . It is rotated by means of a pawl and ratchet actuated by a rotary step by step magnet R^2 , and it is held in the position to which it is turned by a stop pawl controlled by the release magnet s^{33} . The circuit of the rotary magnet is closed through an interrupter I' similar to I by the sleeve relay R' of the trunk and opened by the relay R^4 , which is controlled by the relay R^5 , which receives current when an idle operator's set has been 90 connected with the trunk. The release magnet s^{33} has its circuit controlled by the relay R^{11} being connected in parallel with the signal light L between the point x and ground. The relay R^{11} is initially controlled by the relay R^{14} which has its circuit made through the switch wiper s^{31} after that wiper has stopped upon the contact s^{36} which is connected through contacts of relays R' and R' of the connected trunk to ground. The wipers s^{29} and s^{30} of the operator's 95 selector switch will then rest upon the contacts s^{34} and s^{35} , respectively, and which are respectively connected to the operator's wires 20 and 19, the switch being stopped in this position by reason of the energization of the relay R^{11} whereby the circuit of the rotary step by step magnet R^2 is broken. It will now be apparent that when a subscriber's line has been connected with a 100 trunk that the sleeve relay R' of that trunk will become energized and a switch S' of an idle operator's set will start up from zero and the wipers s^{29} , s^{30} and s^{31} will sweep over the bank contacts s^{34} , s^{35} and s^{36} , respectively, until these wipers reach the 105 110 115 120 125 130

- contacts connected with the trunk which has been connected up with the calling subscriber, when the switch S' is stopped. After the operator has performed her functions and the connection through the trunk wires 17 and 18 is completed to the wanted subscriber's line, the release magnet s^{38} restores the switch S' to its zero or inoperative position.
- 10 In order to prevent more than one operator's selector switch from being started by a call upon a trunk, interlocking means between these switches is employed and this is shown as consisting of interconnections similar to those employed for preventing more than one of the trunk selector switches from being started up by a single call. Referring to Figures 1 and 9, it will be seen that the interrupter I' connects the stepping magnet R^2 , with the back contact of the armature 2^{r11} of the relay R^{11} and that armature is connected with battery. The front contact of the armature 2^{r11} of the relay R^{11} is connected with the corresponding armature of the corresponding relay of the next operator's set and in turn the front contact of this last armature is connected to the corresponding armature of the next operator's set and so on to the limit of the apparatus. It will now be apparent that when a trunk is connected with a calling subscriber's line, if all the operator's sets are idle, the set having direct connection with the battery will have its switch S' stepped into connection with the calling trunk. If this operator's set is busy, the circuit to the stepping magnet of the next set will be closed and the switch of that set be stepped into connection with the calling trunk, and similarly connections to the stepping magnet of the next trunk will be established if the set last previously mentioned is busy. Thus when several operator's sets are simultaneously used, they are successively thrown into operation progressing from that set directly connected to battery to the limit of the equipment.
- It is to be observed in connection with the interconnections of the operator's sets as just set forth, that if a set or sets are busy, and connection through them has been made to another set, the selector switch of which is being stepped to make connection with the calling trunk, and one of the sets through which connections are made is cleared out, the circuit of the stepping magnet of the switch being stepped will be broken and the switch will be left in whatever position it may happen to be and may cause confusion in the apparatus, unless means are taken to provide against it. To this end contacts a^2 and b^2 , the mechanical arrangement of which is shown in Figure 5, are provided at each operator's selector switch except that one which has its stepping

magnet controlling armature connected directly to battery. These contacts are normally opened by the switch when it is in zero position, but are closed at the initial movement of the switch. One of the contacts is connected to battery while the other is connected to the armature which controls the stepping magnet of the switch to which the particular contacts belong. These contacts therefor maintain the circuit of the stepping magnet of their switch after it has been initially made. In other words, after a circuit has been established for the stepping magnet of an operator's switch, that circuit will be maintained until the desired connection has been established by said switch regardless of whether operator's sets, through which the stepping magnet was initially connected, are cleared out or not. Referring to Figures 1 and 9, to illustrate, and assuming the operator's set including the relay R^{11} to be busy and therefore that relay to be energized, the armature 2^{r11} will come against its forward contact and close the circuit of the stepping magnet of the next operator's set. It will now be apparent that if the relay R^{11} is deenergized, its armature 2^{r11} will fall back, breaking the circuit, at that point, of the stepping magnet of the next set, but the circuit of that magnet, if its switch has been moved from its zero position, will be made through contacts a^2 and b^2 . When, however, the selector switch of this second set has established connection with the calling trunk, the circuit of the stepping magnet will be broken by a relay of its own set and the switch will stop.

In the lower part of Figure 2, I have shown the apparatus which appears in front of one operator, consisting of a set of buttons only. Above these in the figure, I have shown a set of wheels or sections of a drum with the co-operating springs, the motor and the common commutator of the central office sending machine. This machine furnishes the impulses by which the selector and connector switches are worked in order to select the line wanted, and the number of impulses sent as well as their arrangement is determined by means of the operator's keys or buttons. These keys are in three sets K , K' and K^2 , each set having ten buttons controlling contact springs k^1 , k^2 . The springs k^1 of all the buttons in each set are joined to a common wire, and the ends of these three common wires are connected together at the point k^x , from which point the conductor 70 leads, as shown in Figures 2 and 1 to the wiper contacts s^{30} in the switches S' . The spring k^2 of each key is connected to a pen on the appropriate disc or zone on the sending machine drum. When any particular button is depressed, therefore, it connects its individual wire to the common wire 70. The individual wires

of the keys K are marked respectively 71, 72, 73, 74, 75, 76, 77, 78, 79, 80. Similarly the individual wires from the keys K' are marked 81, 82, 83, 84, 85, 86, 87, 88, 89, 90, 95 and the individual wires of the keys K² are marked 91, 92, 93, 94, 95, 96, 97, 98, 99, 100. The sending machine comprises the main commutator D, having a brush d connected to the main battery, and riding over its segments so as to produce regular recurring makes and breaks in a continuous series. In practice this commutator is made with a pair of spring contacts and teeth or cams are formed on the body of the commutator 10 to work these springs up and down, but for convenience of illustration I have shown the brush resting directly on the periphery of the disc. With such a construction in actual practice and considering that this commutator will carry a large number of switching impulses simultaneously, I prefer to make the brush d of carbon. This is a detail, however, which may be varied at will and does not affect the invention. The commutator D is graphically shown as carried on a shaft d⁰ which extends through all of the number wheels forming both the mechanical and electrical connection therewith. The mechanical connection is not shown in the drawing but the electrical connection is indicated by a wire marked d⁰. The number wheels are shown at d', d², d³, d⁴, d⁵, d⁶, d⁷, d⁸, d⁹, d¹⁰, each having a tooth or raised segment of a suitable length 15 to cover the space of the number of teeth on the commutator D equal to the number of impulses the particular wheel is to transmit. Thus the first wheel d' has a single tooth d¹¹, approximately equal in length to only one tooth on the main commutator. The second wheel has a single tooth d¹² approximately equal in length to two teeth on the commutator, and so on. In other words, instead of using a set of number wheels each of 20 which makes and breaks through a number of teeth, I have all the makes and breaks on the main commutator, and in order to send any desired number of impulses, I select a wheel which will maintain connection with the commutator while the desired number of impulses are being produced and are then cut off therefrom. Another peculiarity of the arrangement is that the makes and breaks on the number wheels d', d², d³, etc., 25 are made during the passage of gaps on the main commutator when there is zero potential, and hence there will be no sparking at the number wheel contacts. In order to do this I may either subdivide the commutator surface evenly and equally into alternate conducting and insulating segments and then make each number wheel tooth slightly longer than that of the particular tooth to which it corresponds, or I may make 30 the conducting portions on the commutator

smaller than the insulating portions and make the number wheel teeth of lengths equal to the exact multiple of a unit subdivision.

It will be observed that there are four sets of pens on the number wheels. These will accommodate four sets of keys K', K², etc. If a greater number of digits appear in the numbers to be transmitted, the wheels must be provided with additional sets of 70 springs. The set K has its individual wires connected to the first set of springs d¹³, the set K' has its individual wires connected to the set of springs d¹⁴, and the keys K² are similarly connected to the spring pens d¹⁵. The general direction of rotation of the commutator and the various wheels connected to it is clockwise as shown by the arrows in Figure 2, and the teeth on the wheels come into contact with the spring pens in the order d¹³, d¹⁴, d¹⁵. Thus the number set up on the set of buttons K is transmitted over the wire 70 first, then follows the number set up on the buttons K', and so on. Thus for the number 468 the operator would depress the fourth button in the set K, the sixth button in the set K' and the eighth button in the set K². By tracing the circuits it will be found that when the controlling circuits are closed, 75 which occurs at the beginning of a rotation when the wheels are all in the position shown in Figure 2, current will pass from the main battery to the commutator D, thence to the wheel d⁴, thence by wire 94 to the fourth key in the set K and thence to the wire 70 and so on to the wire 19 and the relay R⁵ in Figure 1, which repeats the impulses over trunk wire 23 to the switches. As the wheels continue their rotation, this circuit will be broken after four impulses have been transmitted, and then a new circuit will be formed carrying current from the battery through the commutator to the sixth wheel d⁶, and thence from the second 80 spring d¹⁴ on that wheel through the wire 86 to the key which is closed, thence to the wire 70 and thence again to the relay R⁵ which repeats to the switches. After these impulses have been sent by this route, this 85 circuit will be broken and a new circuit will be formed from the main battery through the commutator D to the eighth wheel to the third pen thereon, d¹⁵, thence to the eighth key in the set K², which has been closed, 90 thence to wire 70 and to the relay R⁵ as before. The closures between the wheels and successive sets of springs are arranged to be separated by intervals, during which no current at all flows to the wire 70. These 95 intervals are necessary in order to permit the switching circuits to be rearranged so as to produce the proper results in response to the successive sets of working impulses. In other words, having shown herein a set 100

of Strowger switches, I must provide not only the vertical or working impulses in groups, but I must also provide the interposed or rotary impulses between said groups. This is accomplished by means of the wheel d^{17} , which has four teeth set in quadrature, and all adapted to make contact with the single pen d^{18} , which is connected by the wire 170 to the wiper contact s^{29} of the operator's selector switch S' , and thence through the wire 20 to the relay R^6 , which repeats the rotary impulses over the trunk wire 24 to the switches. The wheel d^{17} is insulated from the shaft d^0 and is grounded through the wire 101, this being necessary because the relay R^6 is connected on its other side to battery wire 3. In other words, the repeating relay R^6 , which is controlled by the number wheel, is a grounded relay and so the number wheels take battery impulses from the commutator to work it; but the relay R^6 is on battery, hence the rotary wheel d^{17} uses the ground to work the relays. The reason I make one of these relays grounded and the other to battery, is in order to pull them both up simultaneously when the operator has her telephone set bridged across the wires 70 and 170 in Figure 2.

Hitherto the selector switches referred to as S and S' have been referred to only as regards the electric circuits and contacts with which they are associated and in this connection the diagrammatic illustrations in Figure 1 have been sufficient. The mechanical features of a switch adapted to perform the functions of the switch S' of Figure 1 is shown in Figures 5 and 6. This switch comprises a frame on which is mounted a bank b of contacts consisting of ten rows of contacts of three contacts each. The contacts of the different rows are adapted to be successively engaged by wipers c , d and e which are fixed upon the rotatable shaft f , the three contacts c , d , and e being respectively insulated from each other. A spring g interposed between the shaft f and the frame tends to move the shaft to one limit of movement, when the contact arms carried by the shaft will not rest upon any of the bank contacts as shown in Figure 5. Fixed upon the shaft f is a ratchet h . The teeth of the ratchet are so constructed that a pawl engaging therewith will prevent movement of the shaft under the influence of the spring g . Adapted to engage with the ratchet h are a holding pawl i and a stepping pawl k . The pawl i is pivoted upon the frame and its nose is normally held in engagement with the ratchet by means of a spring l . The pawl k is pivoted to the armature m^2 of the stepping magnet R^2 , which armature is in turn pivoted to the frame of the magnet or upon any other suitable stationary portion. The armature m^2 is normally held retracted by a spring o while the nose of the pawl k is thrown outwardly by means of a spring p extending between the armature m^2 and the tail of the pawl k . The outward movement of the nose of the pawl k is limited and it is guided in its movements by a stationary pin q^3 . In order that the holding pawl i may be disengaged from the ratchet h so that the contacts upon the shaft f may be returned to their normal position under the influence of the spring g , a magnet s^{33} , known as the release magnet is provided. The armature s^3 of the release magnet is retracted by means of a spring t , this armature being limited in its outward movement by a nut u in screw-threaded engagement with a screw v^3 mounted upon the frame of the magnet and extending through the armature s^3 . Obviously the nut u is capable of adjustment along the screw v^3 to permit greater or less movement of the armature s^3 . Carried by the armature s^3 of the release magnet is a resilient arm w which carries a ratchet tooth x' adapted to engage with the lower end of the holding pawl i . An arm y mounted upon the armature m^2 of the stepping magnet overlaps one end of the arm w and is adapted to draw down one end of that arm so that the lower end of the pawl i will clear the tooth x' when the armature of the stepping magnet is attracted. The operation of the apparatus is as follows: Assuming the parts to be in position as shown, as impulses are supplied to the stepping magnet its armature will be attracted a number of times equal to the number of the impulses and at each attraction the pawl k will be thrown forward into engagement with the ratchet wheel and will move that wheel forward a distance depending upon the adjustment of the various parts, which are so adjusted that at the first impulse the wipers upon the shaft f will be moved into engagement with the first row of bank contacts and will be moved to a succeeding row upon each impulse thereafter. The shaft and wipers which it carries will be prevented from retrograde movement by the holding pawl which is forced into engagement with the ratchet h by its spring. A desired row of the bank contacts having been reached in the manner described and the object for which the connection was established having been accomplished, it becomes necessary to return the wipers to their zero or normal position in readiness for another operation as just described. This restoration is effected by deenergizing the release magnet s^{33} , it having been previously energized, when its armature will be retracted, drawing the tail of the holding pawl i with it, and the nose of that pawl will be disengaged from the ratchet h and the wiping contacts will be returned to their initial position. In the next selective operation of

the switch, however, it is necessary that the holding pawl i shall engage with the ratchet h to hold the contacts in any position to which they may be stepped. It, therefore, 5 becomes necessary to release the pawl i from the arm prior to the succeeding stepping operation. This is accomplished by means of the arm y which upon the first energization of the stepping magnet and the attraction of its armature, will draw down with it the free end of the resilient arm w , thereby freeing the pawl i whereupon its nose will be thrown against the ratchet h by the spring l . The contacts a^2 and b^2 operated 10 by the projection z are normally closed, but in the zero position of the switch are separated by the projection z as shown.

It will be noted in regard to the switch just described that the release of the wipers occurs upon the deenergization of the release magnet, the holding pawl being in position to engage the ratchet and restrain the wipers so long as the release magnet remains energized after having once been excited. It may be, however, that it will be of service for the release of the wiper contacts to occur upon energization of the release magnet and for the holding pawl to be disengaged from the ratchet even though the release magnet may be deenergized. Such a condition arises in connection with switch S. A structure adapted for operation in this manner but in other respects like the switch just described is shown in Figure 7. On reference to this figure, it will be seen that the holding pawl i' is pivoted at e' and its nose is normally held in engagement with the ratchet by the spring d' . The tail of this holding pawl is adapted to be engaged by armature s^3 of the release magnet s^1 . When this release magnet is energized, its armature is attracted and the holding pawl i' is moved against the spring d' so that it clears the ratchet, when the wiper contacts are free to return to their initial position. When the armature s^3 is attracted, it carries with it the resilient arm w' , the tooth x^2 of which latches behind the stationary 25 detent s^4 . The holding pawl is thus locked away from the ratchet until, at the first impulse in the stepping magnet s^2 at the beginning of another selective operation the arm y' is drawn downwardly and unlocks the arm w' from the stationary detent, whereupon the holding pawl comes into engagement with the ratchet. The operation of this switch is in all respects similar to that of the switch in Figures 5 and 6 except as to the releasing means above indicated.

The operation of the system can be best set forth by tracing the connections and noting the operations of the various parts of the apparatus which are involved from

the time a call is initiated at the subscriber's station until the conversation has terminated and the apparatus has been restored to its normal condition.

Let it be assumed that a subscriber at a station as A desires to converse. He removes the receiver from the hook when the latter rises and establishes a connection, through his transmitter and receiver, between the lines 1 and 2. A circuit is then established from the free terminal of the battery B through the wire 3, line relay M, armature n , line 1, subscriber's set, line 2 and armature n' to ground. The relay M, being thus energized, attracts its armatures m and m' , a circuit then being established from the free side of the battery B through conductor 3, interrupter I, armature m and conductor 8, to conductor 31 whence the circuit passes to one of the stepping magnets 80 as s^2 of the trunk selector switches as before explained. From the stepping magnet the circuit passes through the conductor 8' and the armature r' of the relay R' to ground. The magnet s^2 is then intermittently energized through the interrupter and this results in the reciprocation of the stepping pawl h (see Fig. 7) and the stepping forward of the wipers of the switch S from one row of bank contacts to the next at each 90 energization until the wiper 14 rests upon the contact to which is connected the conductor 11' leading to the front contact of the armature m' which is connected to the battery conductor 3. From the wiper 14 circuit is made through conductor 27, make-before-break contacts 28 and 29, conductor 30 and relay N' to ground. The relay N' being thus energized attracts its armatures 100 $1^{n'}$ and $2^{n'}$ and connects the trunk conductors 17 and 18 with the trunk extensions 15 and 16 which are connected to the wipers 12 and 13 respectively. 105

When the wiper 14 rests on the contact 11, the wipers 12 and 13, rest on the contacts 9 and 10 respectively. The cut-off relay N is therefore connected in series with the relay R' in a circuit which can be traced from the ground through relay N, extension 5, contact 10, wiper 13, extension 16, 110 armature $1^{n'}$, trunk wire 18 and relay R' to the free side of the battery. The relay N is of high resistance compared to that of relay R and R' and operates on less current so that while the relay N is operated, the relay R' is not operated by reason of the circuit just traced. The relay N, however, is of such resistance that it will carry sufficient current, after the relay R is connected, to hold its armatures after they have been attracted. The relay N being thus energized, attracts its armatures, thereby breaking the circuit of the line relay M at the armature n whereupon the relay M is deenergized and its armatures fall back 115 120 125 130

thereby breaking the circuit of the stepping magnet s^2 whereupon the switch stops. The attractions of its armatures by the relay N, connects the subscriber's lines 1 and 2 with the extensions 4 and 5, contacts 9 and 10, wipers 12 and 13, trunk extensions 15 and 16, armatures $2^{n'}$ and $1^{n'}$ and trunk conductors 17 and 18 respectively. It will now be seen that the tip and sleeve relays R and R' are connected by means of the connections just traced, in series through the subscriber's instrument and between battery and ground.

The relays R and R' being energized, their armatures will be attracted, whereupon the circuit of the release magnet s' will be broken at the armature r and the armature 1^r will come against its front contact 29 which it separates from contact 28, the battery connection of the former contact being maintained through the conductor 40. The armatures 2^r and 3^r are removed from their back contacts thereby breaking the battery connections which otherwise would be established with the trunk conductors 21 and 22 upon the attraction of the armature $2^{r'}$ of the relay R'. The armature r' of the relay R' on being attracted, leaves its back contact and thus breaks the circuit through the stepping magnet s^2 and, coming against its forward contact, makes ground connection, through conductor 41 for the stepping magnet 1^{s2} of the next trunk selector switch as before explained. The attraction of the armatures 1^r and $2^{r'}$ against their front contacts results in the establishing of ground connections through the wires 42' and 43' with the armatures r^4 and $1^{r'}$ of the relay R', and also with one terminal of that relay.

Circuit may now be traced from the ground through the armature $2^{r'}$, conductor 43', armature $1^{r'}$, conductor 44', stepping magnet R², interrupter I', conductor 45', armature 2^{r11} and its back contact and conductor 46' to the battery wire. The magnet R² being intermittently energized will reciprocate its pawl, (see Figs. 5 and 6 and descriptions thereof) stepping the switch forward. When the wiper s^{31} rests upon the contact s^{36} circuit may be traced from the ground through armature 1^r , conductor 42', armature r^4 , conductor 48', contact s^{36} , wiper s^{31} , conductor 49', armature 1^{r11} , conductor 50 and magnet R¹⁴ to battery. In coming against its front contact the armature 2^{r11} establishes connection for the stepping magnet of the next operator's selector switch as hereinbefore described.

The attraction of the armature r^{14} against its front contact closes the circuit from the ground through relay R⁵, conductor 52', conductor 19, contact s^{35} , wiper s^{30} , conductor 53', armature r^{14} , conductor 54', make-before-break contacts 55' and 56', relay R¹¹,

conductor 57', and armature r^{13} to battery. The relays R⁵ and R¹¹ are thus energized and their armatures attracted. As the armature r^{11} comes against its front contact 56', the contacts 55' and 56' are separated thus breaking the circuit just traced, the ground connection of the relay R¹¹ being however maintained through the armature r^{11} and contact 56'. It will be seen that the relay R⁵ has been momentarily energized and that its armature r^5 has been momentarily brought against its front contact, thereby momentarily closing the circuit of the relay R⁴ from the ground through armature $2^{r'}$, conductor 43', relay R⁴, conductor 58', conductor 59' and armature r^5 to battery. The relay R⁴ is then energized and attracts its armatures, the armature 2^{r4} , coming against its front contact and locking battery connection on the relay R⁴ so that its circuit is maintained after the relay R⁵ has been deenergized. The attraction of the armatures r^4 and $1^{r'}$ breaks the connections of the trunk with the operator's stepping magnet and its connections with the multiple contacts s^{36} of the operator's selector switches, the ground connection for the relay R¹⁴, formerly made through the contact s^{36} , being maintained by the armature 1^{r11} which has been attracted against its front contact and which is connected to ground. The armature 2^{r11} has also been attracted against its front contact whereby circuit is established from battery through conductor 46', armature 2^{r11} and the front contact thereof to point α whence a portion of the current passes by light L to ground and the other portion passes through release magnet s^{33} to ground. The release mechanism is thus set to engage the holding pawl of the switch S' (see Fig. 5) and the operator is notified of a call by the lighting of the lamp.

Connection may now be traced from battery through relay R⁶, conductor 20, contact s^{34} and wiper s^{29} to conductor 170. Connection may also be traced from ground through relay R⁵, conductor 52', conductor 19, contact s^{35} , wiper s^{30} , conductor 53' and armature r^{14} to conductor 7⁰.

Referring now to Figure 2, it will be seen that the conductors 170 and 70 are adapted to be connected by means of the pressure of a button O with the conductors 127 and 128, which lead to an operator's set of usual construction and hence not shown. It will be seen that upon the depression of the button O, that a circuit will be completed from the battery wire at one side of the relay R⁶ through that relay the operator's set, and the relay R⁵ to ground. Talking current will thus be supplied to the operator's set and also the relays R⁵ and R⁶ will become energized, whereupon they will attract their respective armatures 1^{r5} and r^6 and one of the operator's conductors 20 will be con-

nected with the trunk conductor 21 while the other operator's conductor 19 will be connected with the other trunk conductor 22. It will now be apparent that the operator's set and the calling subscriber's instrument will be so connected that conversation may be had.

The operator's set and subscriber's instrument having been placed in conversational communication as described, the operator inquires of the subscriber the number of the wanted subscriber's station. Let it be assumed that this number is 468. The operator depresses the fourth key of the set K, the sixth key of the set K', eighth key of the set K². In this manner the conductors 94, 86, and 78 are connected with the common point k^x, these conductors being respectively connected with the pen d¹³ of the drum section d⁴, the pen d¹⁴ of the section d⁶ and the pen d¹⁵ of the drum section d⁸. The commutator D is driven by a motor M³ and, the motor supposed in the particular apparatus shown to be normally at rest, it becomes necessary to start the motor and commutator. To accomplish this, the operator depresses the button O' and thereby connects the conductor 130, which is connected to one terminal of battery, to the conductor 131 and thence through the conductor 132 to the relay R¹² and to ground. The relay R¹² being thus energized, its armatures r¹² and 1^{r12} are attracted when circuit will be closed from the battery wire 109 through the last mentioned armature, conductor 133 and relay R¹³ to ground. The relay R¹³ being thus energized will attract its armatures r¹³ and 1^{r13}. The circuit of the relay R¹¹ to battery through the armature r¹³ is thus broken but this connection is made through the armature r¹² of the relay R¹² whereby the control of the relay R¹¹ is transferred from the relay R¹³ to the relay R¹². Circuit may be traced also from the motor conductor 134 through the armature 1^{r13} and a suitable generator and a motor starter as indicated which may be of any well known type to the other motor conductor 135. The motor will thereupon start up and place the commutator in operation. There is also set in operation a starting disc d⁸ which is of conducting material with the exception of insulating segment 136 upon which the pen 137 normally rests. After the motor and with it the commutator, starting disc, rotary disc and drum sections are set in operation by the depression of the key O', as described the pen 137 will ride off the insulating segment and maintain the circuit initially closed by the depression of the button O'. This circuit being closed the motor, commutator and disks will continue to revolve until the pen 137 again rests upon the insulating segment 136, when the circuit will be broken and the apparatus

will stop. During this rotation, first the pen d¹³ corresponding to the disk d⁴ will be engaged by the contact segment upon the said disk, which is of such a length as to maintain the contact with the pen during four impulses of current through the commutator. The circuit over which these impulses are sent, may be traced from one terminal of the battery to the brush d thence through the commutator, the conductor d⁹¹ to the shaft of the drum thence through the drum to the segment of the disk d⁴, the pen d¹³, the conductor 94, the contacts of the fourth button of the row K to the point k^x thence through the conductor 80 70 to the contact s⁸⁵ of the switch S', conductor 19 and relay R⁵ to ground. At each of the four impulses, the relay R⁵ will be energized and attract its armature 2^{r5} against its back contact connected with the battery B. At each impulse, therefore, the tip side 23 of the trunk will be connected with battery and the impulses will be repeated over this side of the trunk to operate the automatic selector and connector 75 switches as before described; the next operation consists of the sending of a rotary impulse, occasioned by the coming in contact with the pen d¹⁸ of one of the conducting projections upon the disk d¹⁷. This action causes the closure of a circuit from the ground through a conductor 101, disk d¹⁷, pen d¹⁸, conductor 170, contact s⁸⁴, of the switch S', conductor 20, and the relay R⁶ to the battery wire 3. Each projection 80 85 on the disk d¹⁷ is of such length as to transmit but one impulse and this impulse passing through the relay R⁶ through the circuit just traced, the relay last mentioned attracts its armature 1^{r6} against its back contact thereby connecting the sleeve side 20 of the trunk momentarily with the battery wire 3, when a rotary impulse is transmitted over the sleeve side for working the side switches of the automatic selector and connector switches as before indicated; after the sending of the rotary impulse as described, the conducting segment of the disk d⁶ comes in contact with its pen d¹⁴. Then 90 95 six impulses are sent over the conductor 86 100 to the point k^x, whence circuit is the same as before, through the relay R⁵ and six vertical impulses are transmitted over the tip side 23 of the trunk. The disk d¹⁷ then sends another rotary impulse over the 105 sleeve side of the trunk as before and eight vertical impulses are then transmitted over the tip side by reason of the contact upon the disk d⁸ coming in contact with its pen d¹⁵, connected with the conductor 78 through 110 which connection is established to the point k^x, the circuit being otherwise the same as before through the relay R⁵. This is followed by the sending of a rotary impulse by the disk d¹⁷ and then the apparatus is 115 120 125 130

brought to a stop by reason of the pen 137 riding upon the insulating segment 136.

- At the close of the operation just described, the wanted subscriber's line, unless it is busy, will have been connected as before described. The entry of the pen 137 upon the insulating segment 136 at the end of the connecting operation breaks the circuit as before traced through the relay R¹² which 10 thereupon releases its armature thereby breaking the circuit of the relay R¹¹ which in turn releases its armature 2¹¹ thereby breaking the circuit of the release magnet s³³ when (see Fig. 5) the holding pawl i will 15 have its nose removed from engagement with the ratchet upon the switch shaft and the switch will return to its zero position, thus leaving the operator's set idle in readiness to perform the connecting operation for 20 another connecting trunk and its subscriber's instrument. The circuit of the relay R¹³ will be broken at the armature 1¹² whereupon the motor circuit will be broken at the armature 1¹³. 25 Connection having been established as described, between two stations, the hanging up of the calling subscriber's receiver breaks the circuit through the relays R and R' whereupon the former releases its armatures 30 which fall against their back contacts. The armature r connects the release relay s' to battery whereupon the holding pawl is retracted from the ratchet on the switch shaft and the switch returns to zero. The armatures 2^r and 3^r, respectively, place battery on the trunk conductors 21 and 22 simultaneously. This results in the simultaneous 35 energization of the relays V² and V³ the circuit of the relay V² being traceable from the trunk conductor 43 through relay V² and conductor 65 to ground while the circuit of the relay V³ is traceable from the trunk conductor 44 through the relay V³ to ground. Relays V² and V³ having been 40 thus energized and their armatures attracted, circuit may be traced from the battery wire 52, release relay Q', conductor 53, conductor 64, bank contact s²², wiper s²⁰, release relay Q, conductor 38, side switch arm 45 s¹⁴ and conductor 39 to ground. The release relays Q and Q' being thus energized will attract their armatures when the circuits of the release magnets q' and q of the 50 switches S² and S³, respectively, will be closed whereupon those switches will be released and will return to their normal positions.

The breaking of the circuit of the relay R through the relay R' does not cause the release of the armatures of the latter as its circuit is maintained through the cut-off relay N, sufficient current flowing to hold the armatures, after they have been attracted. Upon the restoration of the 60 switch S however, the circuit of the relay 65

R' through the relay N, will be broken and the armatures will fall back, armature 2^r breaking the circuit of relay R⁴ whereupon its armatures will fall back and the apparatus is then in readiness to connect other 70 subscribers.

Having thus described my invention what I claim and desire to secure by Letters Patent is:

1. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, all of the switches specified being 75 normally in a zero or inoperative position, and adapted to be started up to test and connect with bank terminals in their numerical order, substantially as described.

2. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, all of the switches specified being 80 normally in a zero or inoperative position, and adapted to be started up to test and connect with bank terminals in their numerical order, substantially as described.

3. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with release or restoring means for all of said switches, substantially 95 as described.

4. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with driving means for the primary selector switches controlled by the calling subscribers, and driving means for the operators' switches controlled by the primary selector trunks, substantially as described.

4. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with driving means and release or restoring means for the primary 125

5 selector switches controlled by the calling subscribers, and driving means for the operators' switches controlled in the use of the primary selector trunks, substantially as described.

10 5. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with driving means and release or restoring means for said primary selector switches controlled by the calling subscribers, and driving means and release or 20 restoring means for the operators' or secondary switches controlled in the use of the primary selector trunk, substantially as described.

25 6. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with driving means and release or restoring means for the primary selector switches controlled by the calling subscribers, driving means and release or restoring means for the operators' switches controlled in the use of the trunks, and driving means for the forward or calling selector switches controlled by the operator, substantially as described.

40 7. In a telephone exchange system, a number of subscribers' lines, a number of trunks less than the number of lines, each trunk terminating at one end in a primary selector switch, and at the other end in a first selector switch, an operator's circuit and apparatus including a telephone set and a sending device, and an automatic switch associated with the operator's circuit and containing terminals of a number of said trunks, together with driving means and release or restoring means for the primary selector switches controlled by the calling subscribers, driving means and release or restoring means for the operators' switches controlled in the use of the trunks, driving means for the forward or calling selector switches controlled by the operator, and release or restoring means for the said calling selector switches controlled over the lines connected, substantially as described.

45 8. In a telephone exchange system, a plurality of subscribers' lines, a number of

trunks less in number than the number of lines, an operator's circuit including a telephone set and an impulse sending device, means for automatically connecting a calling line with any one of said trunks, thereby rendering the said trunk busy, means for automatically connecting the operator's sending device with said busy trunk and means for automatically connecting said trunk with a wanted line.

15 9. In a telephone exchange system, subscribers' lines, a number of trunks less than the number of lines, an operator's impulse sending device, means for automatically connecting a calling line with a trunk, means thereupon becoming active for automatically connecting the operator's sending device with the busy trunk and automatic switches for completing the connection to a wanted subscriber, said switches being controlled by impulses from the operator's sending device, together with restoring means for the connecting means.

20 10. A telephone system including a calling subscriber's line, terminals therefor at an exchange, a central office link-circuit, adapted to be automatically connected with said line on initiation of a call, an operator's position, a trunk line leading thereto, a signal for said trunk line, an electrically controlled selective switch at the exchange, means for initiating travel thereof to connect said link-circuit and trunk line in response to the operation of said selective switch, a called subscriber's line, terminals therefor at the exchange, operator's means for transmitting directive currents over said trunk line to establish a connection from the terminals of the calling line to terminals of the called line, with means for thereon freeing said trunk line.

25 11. A telephone system including a calling subscriber's line, terminals therefor at an exchange, a central office link-circuit, adapted to be automatically connected with said line on initiation of a call, an operator's position, a trunk line leading thereto, an electrically controlled selective switch at the exchange, means for initiating travel thereof to connect said link-circuit and trunk line in response to the operation of said selective switch, a called subscriber's line, terminals therefor at the exchange, operator's means for transmitting directive currents over said trunk line to establish a connection from the terminals of the calling line to terminals of the called line, with means for thereon freeing said trunk line.

30 12. A telephone system including a calling subscriber's line, terminals therefor at an exchange, a central office link-circuit, adapted to be automatically connected with said line on initiation of a call, an operator's position, a trunk line leading thereto, an electrically controlled selective switch at

- the exchange, means for initiating travel thereof to connect said link-circuit and trunk line in response to the operation of said selective switch, a called subscriber's line, terminals therefor at the exchange, directly operable selective switches associated with said link-circuit, operator's means for electrically controlling adjustment of said selective switches to complete a connection from terminals of the calling line to terminals of the called line, a circuit by which said control is exercised including said trunk line and said link-circuit, and means for disconnecting said trunk line from said link-circuit when said telephone lines have been connected.
13. A telephone system including telephone lines, directly operable selective switches including first selectors for connecting said lines in pairs for conversation, operators' impulse transmitters for adjusting said switches, trunk lines individual to said transmitters respectively, extending to points adjacent to said selectors, a signal for each said trunk line, automatic means intermediate of said trunk lines and selectors for interchangeably connecting the same, and selective apparatus for connecting said selectors with calling lines, the connection of

a selector with a calling line being effective 30 to actuate said automatic means.

14. A telephone system including telephone lines, directly operable selective switches including first selectors for connecting said lines in pairs for conversation, operators' impulse transmitters for adjusting said switches, trunk lines individual to said transmitters respectively, extending to points adjacent to said selectors, a signal for each said trunk line, automatic means intermediate of said trunk lines and selectors for interchangeably connecting the same, selective apparatus for connecting said selectors with calling lines, the connection of a selector with a calling line being effective to 40 actuate said automatic means, and circuit changers at said transmitters effective, when impulses to complete connections are transmitted, to automatically disconnect selectors connected with them, whereby said 50 transmitters become available for other use.

In testimony whereof I affix my signature in presence of two witnesses.

EDWARD E. CLEMENT.

Witnesses:

JOSEPH L. WRIGHT,
CHARLES LOWELL HOWARD.
